CONTAINER CAP OR CLOSURE

Charles Hammer, Garden City, N. Y.

Application July 21, 1937, Serial No. 154,747

7 Claims. (Cl. 215—46)

This invention relates to caps or closures for containers or receptacles, the object of the invention being to provide an improved preformed, rotatable, severable reseal cap whereby a container or receptacle such as a bottle or jar may be effectively sealed and resealed and yet so constructed that, when replaced on the container, the cap will indicate that the container has been opened and thus prevent tampering with the 10 contents thereof.

A further object of the invention is the provision of an improved cap severable without the use of objectionable scoring, score lines or tear-off strips.

15 A further object of the invention is the provision of a preformed, rotatable, severable cap provided with means for sealing both the upper edge and the mouth or neck of the container.

In the manufacture of severable caps, it has 20 been the practice to accomplish this result either by scoring the cap so as to enable one part of the cap to be severed from another along the score lines or by providing tear-off strips.

The art has recognized that score lines are 25 objectionable because of the difficulty of accurately gauging the depth of the score lines since, if not scored deeply enough, the cap will not tear, or will tear unequally. Consequently, the accuracy required has made the caps difficult 30 to manufacture and, therefore, objectionable to manufacture especially in view of the fact that repeated use of scoring tools affects their efficiency and causes complaint by customers.

Tear-off strips are also highly objectionable 35 since frequently it is difficult to sever the strip along a predetermined line resulting in but a portion of the band being removed and requiring the application of tools to remove the cap. Furthermore, it is not infrequent that manipulation of such strips results in injuries to the hands of the user which have sometimes proven to be of serious character. Consequently, customers have taken a strong dislike to such style of caps. Therefore, it is the object of the present improvement to provide a severable cap which is not dependent upon either score lines or tear-off strips 40 or the application of tools to insure its removal.

Metal caps or closures which would indicate 45 tampering with the contents of a container have been patented but either they have not proven very successful or they are of that form in which the cap is made of some thin pliable metal which will permit the cap to be pressed or molded on to the container to conform to the shape thereof, 50 in other words, caps of pliable metal in which

the locking elements such as threads are formed when the cap is applied to the container and, therefore, in handling they are easily bent out of shape and are not efficient in resealing the container as is a preformed metal cap, that is, 5 one in which the metal is sufficiently rigid to permit the cap with its locking elements or threads to be formed on a machine and applied to the container without the necessity of shaping or molding it thereon which requires time and 10 is expensive, while its re-use to preserve the contents of the container, due to its light flimsy character, is materially interfered with.

Another object of the invention, therefore, as hereinbefore stated, is to provide an improved 15 preformed cap, that is, one in which the cap may be efficiently and inexpensively made by machinery and shipped in quantities for quick and easy application to containers without the molding or shaping of the threads while on the 20 container.

Furthermore, it has been the practice to use, in 25 connection with rotatable caps, sealing disks for sealing the edge of the container but I believe I am the first to provide a combined severable cap and sealing medium which will not only indicate that the contents of the container have been tampered with but will efficiently seal the upper 30 edge of the container and also the interior neck thereof.

Therefore, one of the objects of the present improvement is the provision of an improved cap 35 readily severable without the use of objectionable tear-off strips or score lines to indicate tampering with the contents of the container and having combined therewith a sealing medium of such form that it will efficiently seal not only the upper edge of the container but also the interior neck.

In the drawing accompanying and forming a 40 part of this specification,

Fig. 1 illustrates in section this improved cap applied to the neck of a container such as a bottle.

Fig. 2 illustrates this improved cap in section 45 partly rotated in a direction opposite to that required for its application.

Fig. 3 illustrates this improved cap in section and having the improved sealing medium attached thereto.

Fig. 4 illustrates the upper portion of a container 50 with the cap severed and the reseal part thereof removed.

Fig. 5 is an enlarged view of a portion of the cap illustrating the compressed, mill-weakened, severable flange, and

Fig. 6 illustrates the manner in which the mill-weakened flange is stretched during the rotation of the cap off of the container to sever it along the apex of the flange shown in Fig. 5.

5 Similar characters of reference indicate corresponding parts in the several views.

Before explaining in detail the present improvement and mode of operation thereof, I desire to have it understood that the invention is not limited to the details of construction and arrangement of parts illustrated in the accompanying drawing since the invention is capable of other embodiments, and that the phraseology employed is for the purpose of description and not of limitation.

15 In the preferred form of cap herein shown, it is illustrated as a threaded cap although, obviously, it could be made with any suitable rotatable locking elements if desired and the improvements may be used with various styles of caps. In the present instance the cap comprises a top 2 and a depending skirt 3 having locking elements such as threads 4 formed on the skirt.

20 Below these locking elements, the cap is provided with an annular mill-weakened exteriorly projecting compressed flange 5 having therebelow a depending portion 6 which may be readily bent or spun around a shoulder 7 of the container, thereby permanently securing the lower 25 part of the cap to the bottle, this bending, of course, taking place after the cap has been completely rotated on to the container.

30 The lower portion 5' of the skirt of the cap and the upper portion 5'' of the depending portion 6 are milled whereby they are of less thickness, as at 21, thus weakening this portion of the cap and it is at this thinned area that the cap is provided with the outwardly extending compressed flange 5.

35 40 In practice, if preferred, the milled portion at or adjacent to the apex of the annular severable flange may be scored, as indicated by the dotted lines in Figs. 1 and 3, which also indicate the bend of the material, thereby further to weaken it if found desirable sense, in view of the fact that the weakened portion of the cap does not depend entirely upon such scored line, the objectionable features of such scoring, as hereinbefore referred to, are not present.

45 50 The cap may be provided with a suitable exteriorly knurled portion by means of which the cap may be rotated off or on to the container, as desired.

55 The cap may be used with suitable liners Fig. 1, or with a sealing medium such as a flanged cork 26, see Fig. 3, the part 27 of which projects into the neck of the container and effectively seals the same while the flanged portion 28 thereof overlaps the upper edge of the neck and also 60 seals this portion of the container. The flange 28 also effectively secures the cork within the cap, it being interlocked therewith. For this purpose, the outer edge of the flange is squeezed into an annular recess formed in the cap as 65 at 29.

70 Thus, in practice, the combined cork and cap may be applied or removed in a single operation, the rotation of the cap on to the bottle tightly compressing the cork thereinto and, at the same time, the rotation of the cap in the opposite direction removing the cork with the threaded portion of the cap leaving the lower portion 6 spun around the shoulder of the container, see Fig. 4.

75 80 In the present improvement, the gradual ro-

tation of the cap off of the container results in opening and spreading the annular severable projection 5, see Figs. 2 and 6, thus further weakening the already weakened or partially cracked metal at the apex of the projection, and as the continued rotation of the cap off of the container takes place, this will readily break and separate the cap on a circumferential line at the apex of the projection without the necessity of a tearing action such as heretofore necessary when tear-off strips were provided. Therefore, in the present improvement, not only is the cap more readily and quickly severed but this spreading action draws the two walls 5' and 5'', see Fig. 6, apart and so lengthens them that the two parts will not properly fit together thereafter. Consequently, when the upper part of the cap is turned on to reseal the bottle, as the two parts no longer fit together, it can be readily detached both by the hand and the eye that the container has been unsealed and tampered with.

85 90 Thus, it will be seen that when the cap is rotated off of the container, that portion of the cap having the locking threads will be broken away along the mill-weakened apex of the annular projection 5, leaving the lower part of the cap 6 permanently secured to the bottle at the shoulder and with a raw edge 30, see Fig. 4, projecting upwardly since this depending portion 6 is unweakened and, consequently insures the severance of one part of the cap from another along the apex of the projection so that, while the threaded portion of the cap may be replaced to reseal the bottle to preserve its contents, it is impracticable effectively to replace it to conceal this edge.

95 100 Consequently, the user will immediately know that the bottle has been previously opened or tampered with, with those caps that merely have a depending skirt provided with a slot or scored weakened lower portion and no outwardly extending annular ridge or projection, there is nothing to indicate when the cap has been replaced that the bottle has been opened previously because the adjacent portions of the depending skirt can be brought so closely together as to appear practically as though the cap had never been removed. In other words, neither the eye nor hand can readily detect the fact that the cap portions have been previously separated.

105 110 In the present improvement, however, not only will the stretched and projecting raw edge of the separated portions of the cap indicate that the cap has been previously removed or tampered with by inspection, but the raw edge will indicate to the hand of the user such fact and this cannot well be concealed by any manipulation of the cap portions.

115 120 Therefore, I apprehend that I have provided a severable cap which not only can be preformed and, hence, made in quantities prior to their applications to containers, but I have provided one which will effectively and efficiently prevent tampering with the contents without detection.

125 130 The term "mill-weakened" as used herein, has reference to that particular mechanical action in which a milling cutter is used to cut fine grooves or indentations across the face of the metal and in milling this cap, the metal can be almost cut through or even perforated and thus so weakened that, in rotating the cap off of the container, the parts thereof will be readily severed without the use of tear-off strips or scoring.

135 140 It is to be understood that, by describing in

detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made or all of the modes of its use, I claim:

1. A closure cap comprising a skirt having preformed locking elements for rotatably securing the cap on to a container, a depending portion adjoining said skirt and adapted to be bent around a shoulder of a container, and a weakened outwardly extending projection at the juncture of said skirt and depending portion and extending beyond the plane of said skirt and depending portion with its walls substantially in juxtaposition, enabling the separation of the skirt and depending portion upon rotation of the cap off the container, said closure severable only at the juncture of the skirt and depending portion.

2. A closure cap comprising a skirt having preformed locking elements for rotatably securing the cap on to a container, a depending portion adjoining said skirt and adapted to be bent around a shoulder of a container, and an outwardly extending projection at the juncture of said skirt and depending portion with its walls in substantial juxtaposition and its apex beyond the plane of the skirt and depending portion and weakened, enabling the separation of the skirt and depending portion upon rotation of the cap off the container, substantially at the apex and midway of said projection.

3. A closure cap comprising a skirt having preformed locking elements for rotatably securing the cap on to a container, a depending portion adjoining said skirt and adapted to be bent around a shoulder of a container, the lower portion of said skirt and the top portion of said depending portion having less thickness than the remainder of said skirt and depending portion, and an outwardly extending projection having its apex at the juncture of said skirt and depending portion enabling the separation of the skirt and depending portion upon rotation of the cap off the container, said closure severable only at the juncture of the skirt and depending portion.

4. A closure cap comprising a skirt having preformed locking elements for rotatably securing the cap on to a container, a depending portion adjoining said skirt and adapted to be bent around a shoulder of a container, the lower portion of said skirt and the top portion of said depending portion having less thickness than the remainder of said skirt and depending portion, and an outwardly extending projection having its apex at the juncture of said skirt and depending portion

and extending beyond the plane of said skirt and depending portion with its walls substantially in juxtaposition, enabling the separation of the skirt and depending portion upon rotation of the cap off the container, said closure severable only at the juncture of the skirt and depending portion, said cap also having a score within the area of said outwardly extending projection.

5. A closure cap comprising a skirt having preformed locking elements for rotatably securing the cap on to a container, a depending portion adjoining said skirt and adapted to be bent around a shoulder of a container, the lower portion of said skirt and the top portion of said depending portion having a milled surface, thereby weakening it, and an outwardly extending projection having its apex at the juncture of said skirt and depending portion and extending beyond the plane of said skirt and depending portion with its walls substantially in juxtaposition, enabling the separation of the skirt and depending portion upon the rotation of the cap off the container, said closure severable only at the juncture of the skirt and depending portion.

6. A closure cap comprising a skirt having preformed locking elements for rotatably securing the cap on to a container, a depending portion adjoining said skirt and adapted to be bent around a shoulder of a container, and a weakened outwardly extending projection having its apex at the juncture of said skirt and depending portion and extending beyond the plane of said skirt and depending portion with its walls substantially in juxtaposition, enabling the separation of the skirt and depending portion upon rotation of the cap off the container, said closure severable only at the juncture of the skirt and depending portion, said cap having therein a sealing medium overlapping the upper edge of the container and projecting thereinto to seal the interior thereof.

7. A closure cap comprising a skirt having preformed locking elements for rotatably securing the cap on to a container, a depending portion adjoining said skirt and adapted to be bent around a shoulder of a container, and a weakened outwardly extending projection having its apex at the juncture of said skirt and depending portion and extending beyond the plane of said skirt and depending portion with its walls substantially in juxtaposition, enabling the separation of the skirt and depending portion upon rotation of the cap off the container, said closure severable only at the juncture of the skirt and depending portion, said cap having therein a sealing medium overlapping the upper edge of the container and projecting thereinto to seal the interior thereof, said sealing medium interlocked with the closure and removable therewith.

CHARLES HAMMER.
